(57) **CLAIM**

I claim the ornamental design for a wireless mailbox signaling system with remote station, as shown and described.

DESCRIPTION

FIG. 1 is a perspective view of a wireless mailbox signaling system with remote station showing my new design; the broken lines depict environmental structure for illustrative purposes only and form no part of the claimed design;

FIG. 2 is a front elevational view thereof;

FIG. 3 is a rear elevational view thereof;

FIG. 4 is a left side elevational view thereof, the right elevational view thereof being a mirror image thereof;

FIG. 5 is a top plan view thereof; and,

FIG. 6 is a bottom plan view thereof.
